DESIGN FOR AN APPLICATOR OR SIMILAR ARTICLE

Herman B. Lermer, Newark, N. J., assignor to Hygienic Tube & Container Company, Newark,
N. J., a corporation of New Jersey

Application October 13, 1936, Serial No. 65,285

Term of patent 14 years

To all whom it may concern:

Be it known that I, Herman B. Lermer, a citizen of the United States, residing in the city of Newark, in the county of Essex and State of New Jersey, have invented a new, original, and ornamental Design for an Applicator or Similar Article, of which the following is a specification; reference being had to the accompanying drawing, forming part thereof.

In the drawing,

Fig. 1 is a perspective view of an applicator or similar article with the plunger in partly retracted position, showing my new design, and

Fig. 2 is a side elevational view of the applicator shown in Fig. 1, with the plunger in partly retracted position.

I claim:

The ornamental design for an applicator or similar article, as shown and described.

HERMAN B. LERMER.
